UNITED STATES PATENT OFFICE.

FRANK YESBERA AND JOSEPH JAMESON, OF TOLEDO, OHIO.

DESIGN FOR A DISPLAY-STAND FOR MERCHANDISE.

42,180.

Specification for Design.

Patented Feb. 13, 1912.

Application filed November 14, 1910. Serial No. 592,410. Term of patent 7 years.

To all whom it may concern:

Be it known that we, FRANK YESBERA and JOSEPH JAMESON, citizens of the United States, residing at Toledo, in the county of Lucas and State of Ohio, have jointly invented a new, original, and ornamental Design for Display-Stands for Merchandise, of which the following is a specification, reference being had to the accompanying drawing, forming part thereof.

The figure is a perspective view of a stand showing our new design.

We claim:

The ornamental design for a display stand for merchandise, as shown.

FRANK YESBERA.
JOSEPH JAMESON.

Signed in the presence of—
PETER F. BARTLEY,
ELTON B. YESBERA.
